UNITED STATES PATENT OFFICE

107,005

DESIGN FOR A RUG

Richard F. Bemporad, New York, N. Y.

Application September 24, 1937, Serial No. 71,775

Term of patent 7 years

To all whom it may concern:

Be it known that I, Richard F. Bemporad, a citizen of Italy, residing at New York, in the county of New York and State of New York, have invented a new, original, and ornamental Design for a Rug, of which the following is a specification, reference being had to the accompanying drawing, forming part thereof.

The figure is a plan view of the rug, showing my new design.

I claim:

The ornamental design for a rug, as shown.

RICHARD F. BEMPORAD.
